UNITED STATES PATENT OFFICE.

HENRY AMSEL AND BENJAMIN REICHARD, OF NEW YORK, N. Y.

EXTENSION-TABLE.

1,153,666.

Specification of Letters Patent. Patented Sept. 14, 1915.

Application filed December 18, 1914. Serial No. 877,890.

To all whom it may concern:

Be it known that we, HENRY AMSEL, a citizen of the United States, and a resident of the borough of Bronx, county of Bronx, city and State of New York, and BENJAMIN REICHARD, a citizen of the United States, and a resident of the borough of Brooklyn, county of Kings, city and State of New York, have invented certain new and useful Improvements in Extension-Tables, of which the following is a specification.

Our improvements relate to table furniture of the "extension" type, in which the ends or halves of the top are slidably connected with relation to each other, so that extension leaves may be inserted or removed from between them to accommodate the table to the varying requirements of use. Heretofore these extension leaves have been detachable and separate adjuncts to the structure,—auxiliary thereto in fact,—and when not in actual use have been stored in any convenient space, more or less accessible according to circumstances, but always more or less remote from the table; and being loose are liable to become separated, mislaid or damaged, so as not to be readily available. Furthermore they are comparatively heavy and difficult to manipulate and place in position with accuracy when desired for immediate use, and are apt to become mixed or misplaced in arrangement with relation to the table and to each other, since they are made to fit together in sequence. And their storage apart from the table structure exposes them frequently to undesirable conditions where they absorb moisture, dirt, &c., or become warped or otherwise damaged, if not actually lost, misplaced, or used for other purposes calculated to cause their deterioration or unfitness for the purpose for which they were originally intended.

All these objections we obviate by our invention which consists essentially in incorporating the extension leaves or sections permanently with the structure of the table itself, in such manner that the table as a whole can be quickly and conveniently extended or contracted as desired without the detachment of any part thereof, all as hereinafter more fully set forth.

In the accompanying drawings, Figure 1, is a top view of the table contracted; Fig. 2, a top view of the table extended; Fig. 3, view of the under side of the contracted

table looking upward; Fig. 4, a sectional view upon plane of line 4—4 Fig. 3; Fig. 5, a view similar to Fig. 3, showing the table extended; Fig. 6, a section taken upon plane of line 6—6 Fig. 5; Fig. 7, is a sectional detail showing one of the extension leaves in position to form an extension of the table top, taken upon plane of line 7—7 Fig. 5; Fig. 8, a similar view showing a leaf retracted, taken upon plane of line 8—8 Fig. 3; Fig. 9, is a perspective view showing in detail one end of the coupling bar by which the ends of the table top are connected; Fig. 10, a detail view of the knuckle joint of one of the folding brackets.

In the drawings herewith filed we have shown the practical application of our invention to an extension table top of ordinary and well known general construction and arrangement of parts, the leg or legs being omitted for convenience of illustration. Thus for the base board B, shown and to which a central leg or support of any ordinary or desired construction may be attached, may be substituted the ordinary frame base supports used where a plurality of legs are provided for the table; and the top of the latter is shown as made with rounded ends, which latter may obviously be of rectangular or other configuration with like result in so far as our invention is concerned.

Rigidly attached to the base board or plate B, are the rail bars R, R, formed with the dovetail tenons r, r, which fit into the correspondingly formed mortises e, and e', in the extension bars E, and E',—bars E, being rigidly attached to one table end top T, and the bars E', being rigidly attached to the other table end top T'. The standards e, e', by which the extension bars E, E', are rigidly secured to their respective table end tops T, T', are of sufficient depth to create a space a, between the under side of the table top and the base board B, rails R, and extension bars E, E', to afford accommodation for the leaves L, L, when retracted and folded one over the other as shown in Figs. 3, 4, and 8.

The table top ends T, T', are connected together by a coupling rod C, which limits the extent to which they may be drawn apart for the interposition of the leaves L, L. This coupling bar C, may be formed with a longitudinal slot c, into which protrude pins c', on the under side of the end

tops T, T', or may be formed with shoulders c^2 , c^2 , for contacting with straps c^3 , c^3 , when the limit of movement is attained, or any other mechanical expedient may be resorted 5 to to restrict the extent of separation between the table ends, and maintain the alinement of the coupling bar C.

The extension leaves L, L, are each of a length equal to one half the width of the 10 table, or approximately so, and each is connected with the base board B, or equivalent stationary part of the structure, by an articulated or folding brace or bracket D, of any suitable construction, that shown in the 15 drawings being an article of commerce, and consisting of the pivotally connected arms d , d' , formed with the contacting shoulders d^2 , d^3 , which (by reason of the tension springs d^4), sustain the parts in the extended position in alinement with each other, to support the outer ends of the extension leaves L, L, when the latter are turned into the same plane as that of the end tops T, T'—it being presumed of course that the 20 latter are separated for the purpose. When thus positioned the inner ends of the leaves L, L, rest upon the coupling bar C, and are supported thereby. To insure a close, snug fit dowel pins p , may be used to join the 25 abutting edges of the extension leaves L, L, and table end tops T, T', in a manner well known in the art; and the table may be otherwise finished in accordance with the custom and requirements of the trade.

30 When it is desired to contract the table the braces D, are bent and folded against the resistance of the springs d^4 , which then tend to hold and maintain the brace members d , d' , in folded relationship to each 35 other, and the leaves L, L, are tucked under into the space a , hereinbefore referred to between the base board B, the rail bars R, the extension bars E, E', and the under side of the table top, the leaves being superposed 40 one over the other as shown in Fig. 4, particularly. That is to say, one half of each full length of extension leaf is slid under the other half, the superposed sections resting upon and being supported by the rail bars 45 R, extension bars E, E', and base B. When the leaf sections L, L, are thus disposed of in the space a , the ends of the table may be readily brought together, covering, protecting and concealing the leaves L, braces D, 50 and other parts positioned below the table top.

55 It will be seen that the coupling bar C, not only connects the end members of the structure, but also performs the important function of a support for the inner ends of the leaf-sections when the latter are in position

for use as a continuation of the table top,—acting in conjunction with the braces D, to sustain said extension leaves against all strain to which they may be subjected in 60 such position and relationship under ordinary conditions of use. It will be seen also that by our construction and arrangement of parts we attain what may be designated, practically as a "self-contained" extension 70 table in that all the component parts thereof are incorporated in the structure, in convenient relation to each other, and with no danger of loss or displacement. And the extension leaves are always in proper relationship to each other and to the table ends, and may be quickly and conveniently positioned for use or nested under the table end tops when not wanted. Furthermore the 75 mechanism employed is simple and not liable to get out of order, and can be manipulated by any one, even a woman or child, without special exertion or inconvenience.

What we claim as our invention and desire to secure by Letters Patent is,

85 1. An extension table of the character designated, comprising a base, rail bars rigidly attached thereto, extension bars slidably connected with said rail bars, table top ends rigidly attached to said extension bars, a centralized coupling bar connecting the table top ends, and extension leaves, foldable braces of pivotally united sections connecting said leaves and base, said leaves being 90 adapted to be positioned to form continuations of the table top ends with their inner abutting ends resting upon said coupling bar, or to be folded under said table top ends, for the purpose described.

95 2. In an extension table of the character 100 designated, the combination of a base, rail bars rigidly secured thereto, extension bars slidably connected with said rail bars, table ends rigidly attached to said extension bars, a centralized coupling bar connecting said 105 table top ends, extension leaves of a length equivalent in length to one half the width of the table pivotally attached to the base on either side thereof by foldable braces, and adapted to be positioned to form continuations of the table top ends with their inner 110 abutting ends resting upon said coupling bar or to be nested overlapping each other under said table end tops, said braces being formed of jointed members, and springs acting to hold and maintain said members in 115 folded position, for the purpose described.

HENRY AMSEL.
